US0D1046895S

(12) **United States Design Patent** (10) Patent No.: **US D1,046,895 S**
(45) Date of Patent: ** Oct. 15, 2024

(54) **DISPLAY SCREEN OR PORTION THEREOF
WITH A GRAPHICAL USER INTERFACE**

(71) Applicant: **Roche Diabetes Care, Inc.**,
Indianapolis, IN (US)

(72) Inventor: **Oleg Novikov**, Vienna (AT)

(**) Term: **15 Years**

(21) Appl. No.: **29/876,050**

(22) Filed: **May 16, 2023**

(56)

(57) **CLAIM**

The ornamental design for a display screen or portion thereof with a graphical user interface as shown and described.

DESCRIPTION

FIG. 1 is a front view of a first embodiment of a display screen or portion thereof with a graphical user interface showing my new design; and,

FIG. 2 is a front view of a second embodiment of a display screen or portion thereof with a graphical user interface showing my new design.

The broken lines illustrate a display screen or portion thereof, and form no part of the claimed design.

1 Claim, 2 Drawing Sheets
